UNITED STATES PATENT OFFICE

171,832

COIN-CONTROLLED AMUSEMENT APPARATUS IN THE NATURE OF A RIDING DEVICE

Ford Se Bastian, Chicago, Ill., assignor to Electro-Snap Switch & Mfg. Co., Chicago, Ill., a corporation of Illinois

Application February 24, 1953, Serial No. 23,738

Term of patent 3½ years

(Cl. D34—15)

To all whom it may concern:

Be it known that I, Ford Se Bastian, a citizen of the United States and a resident of Chicago, in the county of Cook and State of Illinois, have invented a new, original, and ornamental Design for a Coin-Controlled Amusement Apparatus in the Nature of a Riding Device, of which the following is a specification, reference being had to the accompanying drawing, forming a part thereof, and in which:

Fig. 1 is a perspective view of a coin-controlled amusement apparatus in the nature of a riding device, showing my new design;

Fig. 2 is a perspective view of the opposite side thereof;

Fig. 3 is a top plan view thereof; and

Fig. 4 is a front elevational view thereof.

I claim:

The ornamental design for a coin-controlled amusement apparatus in the nature of a riding device.

FORD SE BASTIAN.
